UNITED STATES PATENT OFFICE.

WALTER S. MOODY, OF SCHENECTADY, NEW YORK, ASSIGNOR TO THE
GENERAL ELECTRIC COMPANY, OF NEW YORK.

DESIGN FOR A CASING FOR DYNAMO-ELECTRIC MACHINES.

SPECIFICATION forming part of Design No. 29,373, dated September 20, 1898.

Application filed August 8, 1898. Serial No. 688,120. Term of patent 14 years.

To all whom it may concern:

Be it known that I, WALTER S. MOODY, a citizen of the United States, residing at Schenectady, in the county of Schenectady, State of New York, have invented and produced a new and original Design for a Casing for Dynamo-Electric Machines, (Case No. 798,) of which the following is a specification.

In the accompanying drawing, which illustrates my invention, is shown a perspective view of a motor-casing.

The leading feature of the design is the configuration of the casing, substantially as shown in the drawing.

Referring by letter to the drawing, A represents the main body or casing, which is circular in outline and is provided with feet B for supporting it in position. Extending lat-

erally from the left-hand side of the casing is a supporting lug or projection C. Extending outwardly on the right-hand side of the casing is a second supporting lug or projection D, which is in line with the lug C. On the left-hand side of the casing is provided an opening E in line with the lugs C and D. On top of the casing is mounted a cover F.

I claim—

The design for a casing for a dynamo-electric machine, substantially as shown and described.

In witness whereof I have hereunto set my hand this 4th day of August, 1898.

WALTER S. MOODY.

Witnesses:

B. B. HULL,
M. U. EMERSON.
